WRIST WATCH DIAL

Max Hetzel, Neuchatel, Switzerland, assignor to Centre Electronique Horloger S.A., a firm of Switzerland
Filed Apr. 20, 1965, Ser. No. 84,891

Claims priority, application Switzerland Oct. 30, 1964

Term of patent 14 years

(Cl. D42—1)

FIG. 1

FIG. 2

FIG. 3

FIG. 4

FIG. 5

FIG. 6

FIG. 7

FIGURE 1 is a front elevational view of a wrist watch dial showing my new design;

FIGURE 2 is a similar view showing a modified embodiment thereof;

FIGURE 3 is a similar view showing a further modified embodiment thereof;

FIGURE 4 is a similar view showing another modified embodiment thereof;

FIGURE 5 is a similar view showing still another modified embodiment thereof;

FIGURE 6 is a rear elevational view of the dial seen in FIGURES 1 through 5; and

FIGURE 7 is a side elevational view thereof.

The characteristic feature of my design resides in the combination on the dials disclosed, of an off center hand-hole opening, radial time pips which sequentially increase in length for half the circumference and sequentially decrease in length over the latter half circumference adjacent the dial periphery, and a rectangular opening in the dial for secondary indicia display, all as shown.

I claim:

The ornamental design for a wrist watch dial, as shown and described.
